UNITED STATES PATENT OFFICE.

FRANZ T. M. SCHINDELER, OF CLEVELAND, OHIO.

SERVING DEVICE.

1,103,225.

Specification of Letters Patent. Patented July 14, 1914.

Application filed March 5, 1913. Serial No. 752,145.

To all whom it may concern:

Be it known that I, FRANZ T. M. SCHINDELER, a citizen of the United States, residing at Cleveland, in the county of 5 Cuyahoga and State of Ohio, have invented a certain new and useful Improvement in Serving Devices, of which the following is a full, clear, and exact description, reference being had to the accompanying drawings.

10 This invention relates to serving devices, such as are used on dining tables for the purpose of containing and dispensing crackers, croutons, and like articles of food; and its objects are to provide a device of this 15 character having a hopper in which a quantity of crackers, for instance, may be placed and from which they may gravitate into serving pockets below to replace such crackers as have been withdrawn therefrom; to 20 provide a device of this character which is sanitary, being provided with covers for the serving pockets to protect their contents from dust or other undesirable elements; which is provided with a common 25 operating means for the aforesaid covers, upon the actuation of which the various covers are simultaneously raised; and which is provided with racks for the accommodation of receptacles containing salt, pepper 30 and other seasoning ingredients, commonly associated, and used for the flavoring of soups or the like, for which the crackers are provided.

These and further objects will be apparent as this description proceeds.

In the accompanying drawings forming a part hereof, Figure 1 is a perspective view of my serving device; Fig. 2 a vertical cross section thereof, looking toward the 40 end having the cover-operating mechanism applied thereto; and Fig. 3 is a vertical sectional detail of that end of the device shown in Fig. 2.

Describing the parts by the use of reference characters, 1 and 2 represent the end walls of my serving device which are connected by side plates 3 and 4 secured to the end plates as by rivets, as shown at 5. A bottom 6, comprising a pair of parabolic 45 curved portions which meet in a central longitudinal ridge (as indicated at 7) and which are bent downwardly near their outer edges to form vertical side walls 8, is secured to the end walls 1 and 2 by rivets or 50 screws which pass through lugs 9, projecting inwardly from the ends of the walls 8,

and lugs 10, which are turned toward the center of the device from the ends of the parabolic curved portions, and are secured to the ends by common fastening means. 60 That space inclosed by the upper portion of the end walls and the plates 3 and 4, provides a hopper A which is adapted to be closed by the curved plates 11, hinged at 12 upon rods supported in the end walls 65 1 and 2 and which meet at their upper edges on the medial line of the serving device. These cover plates overbalance toward the center of the device and are retained closed by their own weight, although, 70 if I find it desirable, I will provide a latch or other fastening means for holding them closed.

B represents the serving pockets which are formed by the curved portions of the 75 bottom 6 and the lower, outer portions of the end walls 1 and 2. These pockets have covers 14 which are curved to conform to the shape of the end walls and which are supported upon correspondingly shaped 80 arms 15, pivoted at 16 to the end walls 1 and 2. Those arms 15 which are pivoted to the end wall 2 have inwardly projecting branches 17, the inner ends of which are connected by links 18 to a cross head 19 85 rigidly secured to a plunger rod 20 which is guided through a hole in a bracket 21 carried by the end wall 2 and which is surrounded by a knob 22 which may be engaged by the thumb of the operator to de- 90 press the rod 20 and its cross head 19, the links 18, and the branches 17 of the arms 15, causing said arms to rock upon their pivots 16 and elevate the covers 14 into the position shown in dotted lines in Fig. 2. 95 It will be noted, upon an inspection of the same figure, that the side plates 3 and 4 extend downwardly a sufficient distance to provide restricted passageways C through which the serving pockets B communicate 100 with the hopper A; and this construction provides an automatic check or stop for the feeding of the crackers from the hopper into the pockets, by the presence of the crackers in the pockets choking or blocking 105 the restricted passageways C and thereby preventing further gravitation of the crackers from above until the supply in the pockets has been depleted to the desired extent.

110 A convenient handle is provided for my serving device by a horizontal bar 25, sup-

ported near its ends by a pair of vertical rods 26 which are curved near their lower ends toward the end walls 1 and 2 and terminate in flat portions 27 which may be 5 riveted or otherwise secured to the end walls.

It will be seen from Fig. 3 that the lower portion 28 of the end wall 2 is bent outwardly in a horizontal plane and this horizontal portion provides the bottom plate of a supporting rack for a salt cellar, a pepper duster, and other such containers, the upper plate of the rack being shown at 29. The inner edge of the latter plate is turned 10 downwardly to form a flange 30 by means of which it may be secured to the outer surface of the end wall a convenient distance above the horizontal portion 28 and parallel thereto. The outer edges of the plates 28 15 and 29 may be curved as shown in Fig. 1 and spaced apart by posts 31. As shown in said Fig. 1, the upper plate 29 at the left hand end of the receptacle is provided with holes for the accommodation of a salt cellar, 20 a pepper duster, and a glass, the bottoms of which rest upon the plate 28. While Fig. 3 shows but one of the end walls turned outwardly to provide the bottom plate of the rack, it will be understood that the opposite 25 30 end is treated in a manner identical thereto.

It will be obvious that the serving device may be made of any desired size and provided with any desired number of serving pockets without departing from the spirit of my invention. 35

Having thus described my invention, what I claim is:

In a device of the character set forth, the combination of a receptacle having an inverted V-shaped bottom the sides whereof 40 are downwardly, outwardly and upwardly inclined to provide laterally projecting pockets, side, end and cover plates forming with the central portion of the bottom a storage receptacle or hopper, the lower ends 45 of the sides projecting above and spaced a relatively short distance from the downwardly inclined sides of the bottom to provide restricted passageways therewith, a cover plate for each pocket pivoted at its 50 inner end adjacent to a side plate, arms projecting inwardly from each cover plate, a plunger having a cross head, and links connecting said cross head with said arms.

In testimony whereof, I hereunto affix my 55 signature in the presence of two witnesses.

FRANZ T. M. SCHINDELER.
